UNITED STATES PATENT OFFICE.

PAUL B. PERKINS, OF NORTH SPRINGFIELD, MISSOURI.

HYDRAULIC ENGINE.

SPECIFICATION forming part of Letters Patent No. 325,965, dated September 8, 1885.

Application filed May 11, 1885. (No model.)

To all whom it may concern:

Be it known that I, PAUL B. PERKINS, of North Springfield, in the county of Greene and State of Missouri, have invented certain 5 new and useful Improvements in Hydraulic Engines; and I do hereby declare the following to be a full, clear, and exact description of the invention, such as will enable others skilled in the art to which it appertains to 10 make and use the same.

My invention relates to an improvement in hydraulic engines.

The object is to provide means whereby an engine of any power may be set to run at different predetermined degrees of power and the speed of the line-shaft be kept the same at all the different variations of power, a further object being to maintain economy in the use of water corresponding to the degree of its maximum power at which the engine is run, and, further, to provide means for registering the 20 number of gallons of water used per minute at the several degrees of power and the total number of gallons used during the twenty-four 25 hours.

With these ends in view my invention consists in certain features of construction and combinations of parts, as will be hereinafter described, and pointed out in the claims.

30 In the accompanying drawings, Figure 1 is a plan view, partly in section, of an engine embodying my invention. Fig. 2 is a view of the water-inlet chamber, index, and cylinder in elevation, and Fig. 3 is a plan view of the power-regulator disk-valve.

The general construction of the engine is that of an ordinary steam-engine. A is the cylinder in which the piston B works. C is the rod connecting the piston-rod and crank-shaft D. 40 E is the supporting or bed frame in which the shaft D is suitably journaled. F is the balance-wheel secured on the shaft D, and G is the valve-rod secured to an eccentric, H, on the shaft D.

45 The valve I is of the ordinary sliding cut-off style, and works in an enlarged valve-chamber, K.

L represents the exhaust, and M the water-ports.

50 To the side of the valve-chamber K is secured a water-inlet chamber, N, provided with

an opening, n, leading to the water-supply, and separated from the chamber K by a rotary disk, O, and the cover of the chamber K. A single port, P, is formed through the cover of 55 the chamber K, with which a series of perforations, o o', &c., formed in the disk O, register as the disk is rotated. The areas of the cross-sections of the perforations o' o'', &c., bear a certain predetermined ratio to the full-sized 60 opening o, which corresponds in size to the port P. For example, supposing the size of the opening o be represented by unity, the sizes of the openings o' o'' o''' may be represented by three-fourths, one-half, and one-fourth, re- 65 spectively.

The disk O is operated by means of a stem, Q, which is located in a box, q, passing through the chamber N, said stem being provided with a lever-handle, R, at its outer end. The outside of the cap of the chamber N is provided with an index, consisting, preferably, of two or more circular lines of figures or characters denoting the size of the openings, as compared with the full opening, the number of horse-power corresponding to the several openings, 70 the number of gallons of water used per minute, and the total number of gallons used in twenty-four hours. 75

A small pointer attached to the handle R, as 80 shown at r, is employed to denote the position the handle is to occupy for the use of the several openings. Thus, for example, when the handle is turned so as to bring the pointer r over the line marked one-half, it signifies that 85 the opening, which now registers with the port P, is one-half the size of the full opening o, and the number of horse-power and gallons per minute located at this mark denote the horse-power of the engine when run at one- 90 half full power and the number of gallons of water discharged per minute when run at said power.

A cone of graduated pulleys, S s s' s'', &c., is secured on the engine-shaft D, and a corresponding reversed cone of pulleys, T t t' t'', &c., is secured on the line-shaft D'. The relative lengths of the circumferences of each two corresponding pulleys, S T s t s' t' s'' t'', &c., are such as to correspond with the different sizes 95 of openings in the disk O, as follows: Suppose the full opening o be in use and the band for 100

transmitting the motion of the engine-shaft to the line-shaft be placed on the corresponding pulleys $s^2 t^2$. If, now, it is desired to run the engine at three-fourths of its full power, the handle R will be turned until the pointer r rests over the line marked three-fourths. The result is to cause three-fourths of the amount of water to enter the cylinder in a given length of time, and hence three-fourths of the full number of strokes is obtained during the same time. This would naturally reduce the speed of the line-shaft D'; but by shifting the belt onto the corresponding pulleys, $s' t'$, the speed of the shaft D' is increased relatively to the engine-shaft the same amount that the slowing of the stroke would naturally decrease it, and the speed of the shaft D' is thus maintained at a uniform rate. The successive pairs of pulleys $s t$ and $S T$ serve, in like manner, to increase the speed of the line-shaft to correspond with the decrease in the power.

It is evident that slight changes might be made in the form and arrangement of the several parts described without departing from the spirit and scope of my invention. Hence I do not wish to limit myself strictly to the construction herein set forth; but,

Having fully described my invention, what I claim as new, and desire to secure by Letters

30 Patent, is—

1. The combination, with an engine, a valve-casing, and a valve located within said casing, of a second valve-casing communicating with the first-mentioned casing by a single orifice 35 and a valve located within the second valve-casing for regulating the supply of motor-fluid to the first-mentioned valve-casing, substantially as set forth.

2. The combination, with an engine and a valve for admitting the motor-fluid to the cylinder in amounts bearing predetermined ratios to the full head, of cone-pulleys secured on the engine-shaft and cone-pulleys secured on the line-shaft in reverse position to the pulleys on the engine-shaft, whereby the speed of the line shaft is maintained at a uniform rate during the variations of the power.

3. The combination, with a graduated valve for admitting the water to the cylinder, of a cone of pulleys on the engine-shaft and a reversed cone of pulleys on the line-shaft, whereby the line-shaft is maintained at a uniform speed during the variations of the power, substantially as set forth.

4. The combination, with an engine, a valve-chamber, and a valve located within said chamber, of an inlet-chamber secured to the valve-chamber, a port connecting the two chambers, a rotary valve-disk provided with different-sized perforations adapted to register with said port, and a lever for adjusting said disk.

5. The combination, with an engine, a valve-casing, and a valve, of a second valve provided with a series of different-sized openings, each bearing a predetermined ratio to the full opening, an operating-lever, and a graduated scale or index located in convenient proximity to a pointer on the operating-lever, substantially as set forth.

In testimony whereof I have signed this 70 specification in the presence of two subscribing witnesses.

PAUL B. PERKINS.
